COVER OPERATING MECHANISM FOR SOAKING PITS

Howard F. Spencer, Evans City, Pa.

Application July 18, 1957, Serial No. 672,709

5 Claims. (Cl. 212—4)

This invention relates to new and useful improvements in cover operating mechanism for soaking pits and it is among the objects thereof to provide soaking pit cover carriages having track arrangements for supporting power carriages that can be used as the operating mechanism for raising the soaking pit cover and also as the power means for traversing the cover carriage on its supporting rails.

Conventional soaking pit covers employ operating mechanism that is permanently attached to the cover, and because of the high cost of the operating mechanism such as the cover hoist gear reduction mechanism and motor drives, cover hoist and traversing mechanism for multiple soaking pit installations represents a substantial investment.

In accordance with the present invention, while each of the soaking pit covers is provided with its own traversing carriage, there is no operating mechanism on the cover carriage. The operating mechanism is provided through a separate power carriage that carries the cover lifting mechanism, the speed reduction and drive mechanisms, a single such power car or carriage serving a multiple pit furnace.

In accordance with the present invention, the cover carriages are provided with rails for supporting power carriages that are movable thereon and capable of passing from cover to cover.

It is another object of the invention to provide a cover carriage and power carriage combination in which the power for traversing the cover carriage is supplied by the power carriage through a drive mechanism rendered operative when the pit cover is raised.

It is another object of the invention to provide a rail structure for soaking pit cover carriages and a power car carriage wheel structure and guides that permit the power carriage to be traversed from the tracks of one cover carriage to the tracks of an adjacent cover carriage by means of transmission mechanism carried by the power carriage.

These and other objects of the invention will become more apparent from a consideration of the accompanying drawings constituting a part hereof in which like reference characters designate like parts and in which:

Figure 1 is a top plan view diagrammatically illustrating a plurality of soaking pits with cover carriages and a power carriage, together with a transfer car;

Figure 2 is a side elevational view taken along the lines 2—2, Figure 1;

Figure 3 is an end elevational view taken along the lines 3—3, Figure 1;

Figure 4 is a top plan view of a pair of adjacent soaking pits and covers with the cover carriage and power car in operative position for manipulating the cover;

Figure 5 is a side elevational view taken along the line 5—5, Figure 4, of a portion of the cover carriage and power car with their friction drives in engagement for propelling the cover carriage by power transmitted from the power car;

2

Figure 6 is a view diagrammatically illustrating the friction drive for the cover carriage taken along the line 6—6, Figure 4;

Figure 7 is an end elevational view of the power car and cover carriage taken along the line 7—7, Figure 4;

Figure 8 is a similar view taken along the line 8—8, Figure 4;

Figure 9 is a side elevational view taken along the line 9—9, Figure 4;

Figure 10 is a similar view taken along the line 10—10, Figure 4; and,

Figure 11 is a top plan view diagrammatically illustrating a soaking pit furnace arrangement in connection with the basic plant layout.

With reference to Figures 1, 2 and 3 of the drawing, the numerals 1 and 2 designate soaking pit furnaces, 3 covers therefor, the furnaces being provided with top rails 4 and 5 for flanged wheels 6 that support a cover carriage generally designated by the numeral 7. The cover carriages are provided with rails 8 and 9 for supporting wheels 10 of a power car generally designated by the numeral 11, the power car being provided with hoist mechanism as will be hereinafter described. As shown in Figures 1 and 3, a transfer car generally designated by the numeral 16, is mounted on wheeled axles 17, the wheels of which traverse rails 18. The power car 11 of Figure 2 can be carried by the transfer car 16 which, as shown in Figure 1, permits moving the power car to any bank of soaking pits such as shown in Figure 1, there being three pits shown in a row in each bank.

The rails 8 and 9 of the cover carriages are shown extending parallel with the wheel axles of the cover carriage. The detailed construction of the cover carriage and power car is more clearly shown in connection with Figures 4 to 10 of the drawing. As shown in Figure 7, for example, the power carriage 11 is mounted on the cover carriage 7 and by virtue of its flanged wheels 10 is capable of traversing the rails 8 and 9 on top of the cover carriage 7. The power carriage is capable of traversing the rails 8 and 9 of one cover carriage and passing across the gap between adjacent carriages to the rails 8 and 9 of the adjacent cover carriage by means of what may be termed relay rails 19. These relay rails provided at opposite ends of the power car carriage 11 engage relay rail rollers 20 and 21 and when the power carriage 11 is supported by the rollers 20 and 21, the flange wheels 10 drive the power carriage across the rails from one cover to the other from left to right, as shown in Figures 7 and 8 of the drawings.

The mounting of the power car or carriage with respect to the cover carriage is more clearly shown in Figures 9 and 10 of the drawing. Rails 8 and 9 are shown mounted on the carriage frame 7 and flanged wheels 10 are supported on the rails 8 and 9. The power car carriage frame 11 is journaled on the wheel axle 22, Figures 9 and 10. Shaft 22 is driven by a sprocket chain 23 from a gear reduction mechanism 24 operated by motor 25 to cause the power carriage to traverse on the rails 8 and 9. The power carriage 11 is further provided with hoist mechanism which consists of bell cranks 26 pivotally mounted on the carriage frame 11 at 27, one end of the crank 26 being connected by a link 28 to an eccentric drive 29 operated through a gear reduction mechanism 30 driven by motor 31. Connected at one end to the bell cranks 26 are links 32 having a T-head 33 that is disposed in the T-slot of the cover lugs 34 which are attached to the cover 3 by straps 34a. With the lifting links 32 in their lowered position, the power car or carriage moves to bring the T-heads 33 in alignment with the cover lugs 34 and by operating the hoist motor 31, the bell cranks 26 are rocked to raise the links 32 which, in turn, raise or lift the cover by its straps 34a.

Mounted on the ends of the power carriage frame 11 are friction wheels 35 mounted on a shaft 36, the wheels being driven by a chain 37, Figures 7 and 10. Mounted on the end of the cover carriage frame 7 is a friction wheel 38 driven by a chain 39 from a sprocket wheel 40 mounted on shaft 41. The shaft on which wheel 38 is mounted is journaled at 42 in a bell crank lever, one arm 43 of which is provided with a roller 44 that engages a wear plate 45 of the cover 3. The friction wheel 35 is driven by a motor 46, Figure 4, through transmission or gear reduction mechanism 47. When the hoist mechanism raises the cover 3, it will displace the bell crank 43 and cause the friction wheel 38 to engage the drive wheel 35, as shown in Figure 5, thereby driving the shaft 41 of the wheel 6 to traverse the cover carriage, for example, from the position over the soaking pit opening designated by the numeral 2 in Figure 1, to the space between the rows of pits as shown in Figure 1. The engaged position of the friction rolls is shown in Figure 5 of the drawing, this being the driving position that results when the cover is lifted, as shown by the T-head engaging the cover lug in Figure 5 of the drawing.

The operation of the above-described power carriage and cover carriage mechanisms will now be explained in connection with the diagrammatic views of Figures 1, 2 and 3 of the drawings. As shown in Figure 2, the power carriage 11 has raised the cover suspended from the cover carriage 7 and the cover carriage has been moved to the space between the soaking pit rows 1 and 2 of Figure 1, the cover 3 having been removed from the opening 2 of Figure 1. When covers 3 are in their raised position, wheels 35 and 38 of the friction drive are engaged, as shown in Figure 5. Drive motor 46 is then energized to drive wheels 35 and 38. Wheel 38 will drive wheel axle 41 through chain 39 to rotate wheel 6 of the cover carriage 7 to return above the pit opening 2 and the hoisting mechanism driven by the transmission 30 is then lowered to seat the cover on the pit opening. As the cover is lowered, the friction drive wheels 35 and 38 become disengaged and the cover carriage remains stationary. The power car or carriage 11 is then caused to traverse the supporting rails 8 and 9 of the cover carriage to pass from one cover carriage to another or from one of the end cover carriages to the transfer car 16 by means of which it is transferred on rails 18 to another row of soaking pits similar to #1 and #2.

In Figure 11 of the drawing is shown a different form of basic layout wherein the soaking pits are arranged in fours, there being four groups of four pits shown in Figure 1. In connection with these pits, there are the plant operating tracks designated by the numerals 55 and 56 for ingot buggies and steel delivery tracks. The numerals 57 and 58 designate the walls of a soaking pit furnace; 59 and 60 the covers which are removed from the furnaces 57 and 58. The cover carriages are supported on tracks 4 and 5 and the power car or carriages are supported on the rails 8 and 9 that are provided on the cover carriages. The rails 8 and 9 at the ends of the rows of pits are extended beyond the pits as a parking area for the power car. This is also the battery charging station which may be designated by the numeral 61. Numeral 62 designates the stacks for a battery of soaking pits.

From the foregoing description of the invention, it will be evident that a single power carriage or car may service a plurality of soaking pits by traversing the rails on top of the cover carriages to thereby become the power unit on top of the cover carriage for raising the cover and traversing the cover carriage to the pit opening or closing position.

It is also evident that such equipment may be employed with this type of basic plant layout depending upon the arrangement of the soaking pits. It is evident that the power mechanisms may be either battery powered or connected by trolley or otherwise to electric power circuits.

Although one embodiment of the invention has been herein illustrated and described, it will be evident to those skilled in the art that various modifications may be made in the details of construction without departing from the principles herein set forth.

I claim:

1. In a bank of industrial heating furnaces having openings at the top and covers for said openings with rails on opposite sides of each opening, the combination with a cover carriage for each cover movable on said rails with the cover suspended therefrom, of a power car movable on said carriages, said power car having hoist mechanism for raising and lowering the covers and having drive mechanism for moving the carriages on their supporting rails, said drive mechanism being inoperative when the cover suspended from the carriage is in lowered position.

2. In a bank of industrial heating furnaces having openings at the top and covers for said openings with rails on opposite sides of each opening, the combination with a cover carriage for each cover movable on said rails with the cover suspended therefrom, of a power car movable on said carriages, said power car having hoist mechanism for raising and lowering the covers and said cover carriage having a driven member for moving it on its supporting rails and said power car having a power operated drive member for actuating said driven member of the cover carriage, said drive and driven members being disconnected when the cover hoist support is in its raised position.

3. In a bank of industrial heating furnaces having openings at the top and covers for said openings with rails on opposite sides of each opening, the combination with a cover carriage for each cover movable on said rails with the cover suspended therefrom, of a power car movable on said carriages, said power car having hoist mechanism for raising and lowering the covers and said cover carriage having a driven member for moving it on its supporting rails and said power car having a power operated drive member for actuating said driven member of the cover carriage, said drive and driven members having friction wheels which are engaged when the cover is in its lowered position.

4. In a bank of industrial heating furnaces having openings at the top and covers for said openings with rails on opposite sides of each opening, the combination with a cover carriage for each cover movable on said rails with the cover suspended therefrom, of a power car movable on said carriages, said power car having hoist mechanism for raising and lowering the covers and said cover carriage having a driven member consisting of a friction wheel mounted on an arm of a bell crank lever having a roller mounted on the other arm in the path of movement of the cover to be engaged by the cover in its lowered position and said power car having a drive mechanism consisting of a friction wheel for engaging the friction wheel of the driven member to rotate the same when the roller on the bell crank lever engages the cover.

5. In a bank of industrial heating furnaces having openings at the top and covers for said openings with rails on opposite sides of each opening, the combination with a cover carriage for each cover movable on said rails with the cover suspended therefrom, said carriages having rails disposed transversely of the cover carriage rails of a power car having wheeled axles for movement on said carriages having rollers above said transverse rails and said power car having relay rails at their respective ends extending beyond the edge of the power car to engage said carriage rollers whereby the relay rails are made to bridge the gap between adjacent carriage cars for movement of the power car from one cover carriage to another.
